UNITED STATES PATENT OFFICE.

EDGAR E. SCHLESINGER, OF CHICAGO, ILLINOIS, ASSIGNOR TO WALTER P. MURPHY,
OF CHICAGO, ILLINOIS.

END REINFORCEMENT FOR RAILWAY BOX CARS.

Application filed December 2, 1919. Serial No. 341,860.

To all whom it may concern:

Be it known that I, EDGAR E. SCHLESINGER, a citizen of the United States, residing at Chicago, in the county of Cook and State 5 of Illinois, have invented certain new and useful Improvements in End Reenforcements for Railway Box Cars, of which the following is a specification.

My invention relates to the construction 10 of railway cars, particularly box-cars of wood construction, and has for its object to provide an improved metal reenforcement for the wooden end walls of cars of this type which will strengthen the end walls and 15 framing so that they will withstand the pressures due to the inertia thrusts of the cargo or other causes and also resist the various other stresses to which end walls of railway cars are subjected when in serv- 20 ice. The vertical center portion of a car end supports a large portion of the roof load and is also subjected to more severe cargo thrusts than the portion of the end wall adjacent the side of the car. To 25 strengthen the center portion of the car end I provide a metal sheet having rigidifying ribs and secure the sheet to the car framing in the space between the side sheathing of car and the inner lining. The reinforced 30 metal sheet is preferably arranged in contact with the lining so that the inertia thrust of the cargo against the lining will be transmitted directly to the car framing. The upper end of the metal sheet is preferably 35 connected by diagonally extending bracing members to the side framing of the car so as to effectively resist the weaving strains ad- 40 jacent the roof of the car and to relieve the end plate of a portion of the pressure due to cargo thrusts.

The invention consists in the novel ar- 45 rangements, constructions and combination of parts hereinafter described and claimed for carrying out the above stated objects and such other objects as will appear from the following description of the structures shown in the drawings.

The invention is illustrated in the accom- 50 panying drawings wherein,

Fig. 1 is a front view in elevation of the superstructure of a railway box car showing an end reinforcing structure constructed in accordance with my invention applied to

the car, a portion of the outer sheathing of the car being broken away for the purpose 55 of clearness;

Fig. 2 is a plan view of the structure shown in Fig. 1 with the ridge pole and roof boards removed;

Fig. 3 is a vertical section through the 60 car structure taken on line 3—3 of Fig. 1;

Fig. 4 is a fragmentary sectional plan view taken on line 4—4 of Fig. 3;

Fig. 5 is a vertical section through a rail- 65 way box-car showing a modified form of end reinforcing structure applied thereto;

Fig. 6 is a fragmentary plan view of the structure shown in Fig. 5 with certain parts in section showing the means for securing the reinforcing structure to the side framing 70 of the car;

Fig. 7 is a view similar to Fig. 4 taken on line 7—7 of Fig. 5;

Fig. 8 is a vertical section through a car showing another modification of my im- 75 proved end reenforcement;

Fig. 9 is a fragmentary plan showing the arrangement of the metal reenforcements shown in Fig. 8 and the means for connecting said reenforcements to the side framing of 80 the car; and

Fig. 10 is a fragmentary sectional plan taken on line 10—10 of Fig. 8.

Like characters of reference designate like parts through the several figures of the 85 drawings.

Referring first to Figs. 1 to 4 inclusive of the drawings; 10 designates the corner posts, 11 the end posts, 12 the end belt rail, 13 the end plate, 14 the end sill, 15 diagonal braces 90 extending from the end sill to the end plate, 16 the side plates, 17 the outer sheathing and 18 the end lining which preferably consists of horizontally arranged boards, 95 suitably secured to the end framing.

In the drawings I have shown my invention in connection with a car structure having a particular form of framing though it will be obvious that the invention is not limited in its application to cars of the par- 100 ticular type shown. The reinforcing structure of my invention comprises a vertically disposed metal sheet 20 which is arranged in the space between the outer sheathing 17 and the lining 18 of the car. The vertical edges 105 of the metal sheet are bent outwardly to

form angular attaching and rigidifying flanges 21 which are secured by bolts 22 to the end posts 11—11. The lower end of the metal sheet 20 is flanged inwardly as indicated at 23 and bolted to the floor of the car by bolts 24 which preferably, extend through the end sill 14. The upper end of the metal sheet preferably extends back of the end plate 13 and is secured thereto by a plurality of bolts 25. The metal sheet 20 is reinforced by a plurality of outwardly pressed corrugations 26 which extend vertically from the flooring of the car to the end plate 13 so as to provide a strong and rigid support for the car roof. The corrugations of the sheet preferably merge one into another and the flat portion of the sheet together with the inwardly extending portions of the corrugations are in contact with the lining boards, so that the stresses due to cargo thrusts against the lining are transmitted directly to the car framing; a certain portion of these stresses being transmitted through the reinforced sheet 20 to the end sill 14 and the end plate 13. The upper end of the corrugated sheet 20 is bent inwardly to form an angle 27 which is secured to the side plates 16 by a pair of intersecting braces 28. These braces are riveted at their intersection to a plate 29 and extend diagonally from points adjacent the end posts 11—11 to the side plates; the outer ends of the braces being secured to the side plates 16—16 by means of angular members 30. With this construction the upper portion of the car framing is rigidified so as to resist the weaving strains developed when the car is in motion and also transmits a portion of the inertia thrusts, due to the shifting of the cargo against the lining, directly to the side plates of the car.

In Figs. 5 to 7 inclusive, I have shown a modified form of reinforcing structure consisting of a flat vertically disposed plate 31 arranged in contact with the lining 18^a and secured to the end posts 11^a—11^a with bolts 21^a which, preferably, extend through the lining boards 18^a and end posts 11^a. The lower edge of the sheet 31 is flanged inwardly as indicated at 23^a and secured to the flooring of the car by means of bolts in substantially the same manner as that described in connection with the form of the invention illustrated in the preceding figures and the upper end is secured to the inner face of the end plate 13^a by a plurality of bolts 25^a. The sheet 31 is reinforced by vertically extending angular members 33, preferably Z-shaped in cross section, which are riveted to the sheet 31 by rivets 34. These rigidifying members preferably extend from the flooring of the car to the end plate so as to rigidify the plate 31 throughout its entire length. The upper end of the sheet 31 is bent inwardly to form a flange 27^a which is

connected to the side plates 16^a by means of intersecting bracing members 28^a substantially as shown and described in connection with Figs. 1 to 4, inclusive.

In Figs. 8 to 10 inclusive of the drawings, I have illustrated another modification in which the end wall of a box car is reinforced by a plurality of channel-shaped members 35. These members are arranged between the end posts 11^b—11^b of the car frame and extend vertically from the flooring to the lower edge of the end plate 13^b. The adjacent side webs 36—36 of the channel are formed with overlapping flanges 37 which are secured together by rivets 38, the space between the channel members providing a vertically extending, hollow beam adjacent the vertical center of the car and the channeled portions 40—40 of the channel members providing hollow beams on opposite sides thereof. The side webs 41—41 of the channel members 35 preferably fit against the inner faces of the end posts 11^b—11^b and are provided with flanges 42 which fit between the said end posts and the lining boards 18^b. The reinforcing structure is secured to the end posts by bolts 43. The flanges 37—42 bear against and reinforce the lining boards 18^b and the webs of the channel members bear against the inner surface of the outer sheathing 17^b.

The lower edges of the channel members are preferably bent inwardly to form angular attaching flanges 48 which are secured to the flooring of the car by bolts 44. The upper ends of the channels are bent inwardly to form flanges 45 providing seats for the edge of the end plate 13^b. The upper end of the reinforcing structure is further strengthened by securing the same to the inner face of the end plate 13^b by means of an angular member 46 fastened to the reinforcing structure by rivets 49, the horizontal flange 47 of which angular member is secured to the side plate 16^b by means of intersecting braces 28^b in substantially the same manner as shown in connection with the previously described constructions.

While I have described my invention in connection with certain specific embodiments it will be obvious that further modifications in the structure might be made without departure from the spirit of my invention. I therefore do not wish to be limited to the exact structure shown and described except in so far as specific limitations may appear in the appended claims.

I claim:

1. An end structure for railway cars comprising a vertically disposed metal panel extending from the floor to substantially the roof thereof along the vertical center of the car end and formed with vertically extending corrugations to resist local thrusts of the cargo and to provide a central sup-

- porting structure for the roof load, and angularly disposed flanges for securing said metal panel to the framing of the car.
2. The combination with the outer sheathing and inner lining of a railway car, of a metal panel arranged between said sheathing and lining, and means for securing said panel to the framing of the car.
3. The combination with the outer sheathing end posts, end plate, end sill and inner lining of a railway car, of a metal panel arranged between said sheathing and lining, and means for securing said panel to said end posts, end plate and end sill.
4. The combination with the outer sheathing and inner lining of a railway car, of a metal panel arranged between said sheathing and lining and in engagement with said sheathing and lining to resist the cargo thrusts adjacent the vertical center of the end, and means for securing said panel to the framing of the car.
5. The combination with the outer sheathing and inner lining of a railway car, of a reinforcing structure comprising a metal panel provided with outpressed vertically extending portions and arranged between the said sheathing and lining in engagement with the lining so as to transmit the cargo thrusts adjacent the vertical center of the car end to the framing of the car.
6. The combination with the outer sheathing and inner lining boards of a railway car, of a reinforcing structure for the end comprising a metal panel arranged between said sheathing and lining, in contact with the latter and having outwardly projecting portions extending transversely of said lining boards, the marginal portions of said panel being bent to provide stiffening flanges adapted to be secured to the framing of the car.
7. The combination with the end posts, outer sheathing and inner lining of a railway car, of a reinforcing structure for the end of the car comprising a metal panel vertically disposed between said end posts in the space between said sheathing and lining to reinforce said end posts and resist the cargo thrusts adjacent the vertical center of the car end; the vertical edges of said panel being formed with flanges adapted to be secured to the said corner posts and the body portion being formed with outwardly projecting portions which extend from the floor to substantially the roof of the car.
8. The combination with the end and side framing, outer sheathing and inner lining of a railway car, of a reinforcing metal panel arranged between the said sheathing and lining formed with flanges adapted to be secured to the end framing, and a bracing structure for securing the upper end of said panel to the said side framing.
9. The combination with the end and side framing, outer sheathing and inner lining of a railway car, of a reinforcing metal panel arranged between the said sheathing and lining formed, with vertically extending corrugations and with flanges adapted to be secured to the end framing, and a bracing structure for securing the upper end of said panel to the said side framing.
10. In combination with the wooden end wall of a railway car an end wall reinforcing structure comprising a metal panel arranged adjacent the vertical center of the car end secured to said wooden wall and extending substantially from the floor to the roof of the car, means for rigidifying the upper end of said panel and transmitting cargo thrusts adjacent the vertical center of the end to the side framing of the car comprising bracing members secured to said panel and to said side framing.
11. In combination with the wooden end wall of a railway car an end wall reinforcing structure comprising a metal panel arranged adjacent the vertical center of the car end secured to said wooden wall and extending substantially from the floor to the roof of the car, means for rigidifying the upper end of said panel and transmitting cargo thrusts adjacent the vertical center of the end to the side framing of the car comprising diagonally extending bracing members secured to said panel and to said side framing.
12. In a railway car, the combination with the end wall structure, end plates, side plate and floor structure of the car, of a reinforcing metal panel adjacent the vertical center of the car end extending from the floor to substantially the roof and having its lower end secured to the floor structure its lateral edges to said end wall structure and the upper end to the end plate, and a bracing structure secured to the upper end of said panel and to the side plates of the car.
13. The combination with the outer sheathing, inner lining, end posts, floor structure, end and side plates of a railway car, of a reinforcing structure arranged in the space between the said sheathing and lining comprising a panel made up of a plurality of channel members having overlapping flanges which are secured together along vertical lines, the said channel members being positioned between the end posts and having their upper ends bent inwardly to provide a support for the end plate and their lower ends secured to the floor structure; an angular member securing the upper end of the panel to the end plate, and a bracing structure extending diagonally from said angular member to the side plate of the car.
14. In combination with the wooden end structure of a railway box car, a metal reinforcing panel arranged substantially midway between the sides of the car, bearing

against and attached to said wooden end structure and formed with angular flanges at its upper and lower ends for attachment to the upper and lower frame members of the car end.

15. In combination with the wooden end wall of a railway box car, a metal reinforcing panel arranged substantially midway between the sides of the car and bearing against and attached to said wall, a horizontally disposed metal brace on the inside of the end wall to which the upper end of said panel is secured, and means for anchoring said brace to the side walls of the car.

16. In combination with the wooden end wall of a railway box car, a metal reinforcing panel arranged substantially midway between the sides of the car, said wall comprising a channel-shaped member having side flanges attached to said end wall.

17. In combination with the wooden end wall of a railway box car, a metal reinforcing panel arranged substantially midway between the sides of the car, said wall comprising a pair of channel-shaped members each having flanges at opposite sides secured to said end wall, the adjacent flanges of said members being overlapped one on the other.

18. In combination with the outer end sheathing and inner lining of a railway box car, a metal reinforcing panel extending from floor to roof substantially midway between the sides of the car and comprising a pair of channel-shaped members secured together and provided with side flanges bearing against and secured to said inner lining.

19. In combination with the outer end sheathing and inner lining of a railway box car, a metal reinforcing panel extending from floor to roof substantially midway between the sides of the car and comprising a pair of channel-shaped members secured together and provided with side flanges bearing against and secured to said inner lining, said panel being provided with angularly disposed flanges at top and bottom for attachment to the upper and lower frame members of the car.

20. In combination with the outer end sheathing, inner lining and end posts of a railway box car, a metal reinforcing panel for the middle portion of the car end having a channel configuration and formed with side flanges intervening between said inner lining and end posts.

EDGAR E. SCHLESINGER.
